UNITED STATES PATENT OFFICE.

WILLIAM SMITH, OF SCOTTDALE, PENNSYLVANIA, ASSIGNOR OF ONE-HALF
TO KENNEY & CO., OF SAME PLACE.

PIPE-MOLD.

SPECIFICATION forming part of Letters Patent No. 360,251, dated March 29, 1887.

Application filed January 2, 1886. Serial No. 187,474. (No model.)

To all whom it may concern:

Be it known that I, WILLIAM SMITH, a citizen of the United States, residing at Scottdale, in the county of Westmoreland and State of Pennsylvania, have invented a new Apparatus for Casting Cast-Iron Pipes of Large and Small Diameters; and I do hereby declare that the following is a specification of the same.

This invention relates to certain improvements in molds for casting pipes; and it has for its objects to provide for rapidly and economically producing such castings with the least possible labor and manipulation, as more fully hereinafter set forth. These objects I attain 15 by the means illustrated in the accompanying drawings, in which—

Figure 1 represents a vertical elevation of the flask which I employ in carrying out my invention. Fig. 2 represents a vertical sectional view of the same, showing the interior of the flask and the core; Fig. 3, a vertical elevation of the core detached; Fig. 4, a top or plan view of the flask and its adjuncts; Fig. 5, a transverse horizontal sectional view taken 25 on the line *x x* of Fig. 2; Fig. 6, a sectional view of the base of the flask and the bowl-core of the flask; and Fig. 7 represents detached views of a modification of the expanding-core employed in connection with the flask for molding the pipes.

The letter A indicates the base of the flask, which consists of an annular plate of metal having a countersunk recess, B', on the upper side, for the reception of the base of the bowl-core B of the pipe. The bowl-core consists of a short metal tube having a circular base which sets in the recess in the base of the flask. The upper part of the tube is made flaring on the inside, and the tube is of sufficient height to 35 reach to the shoulder of the pattern, where the bowl commences.

The flask is constructed in sections, as indicated by the letters *a b c d*, which are bolted or otherwise secured together, and it is divided 45 longitudinally and hinged together on one side, so that the parts may be opened to insert the pattern, form the mold, and remove the finished casting. On the side opposite the hinges the flask is provided with latches C and a movable bar, D, which is provided with lugs E,

adapted to engage the latches and lock the parts of the flask together.

F is a lever, which is fulcrumed to one part of the flask, and to which the upper end of the bar is pivoted, so that it may be moved to lock 55 or unlock all of the latches simultaneously.

The letter G indicates the core-barrel, which consists of a metallic shell divided longitudinally, as indicated in Figs. 4, 5, and 6 of the drawings. The longitudinal edges of the shell 60 are formed with V-shaped grooves extending their entire length, for the reception of a wedge-shaped bar, G', of metal, which serves to keep the shell expanded until the pipe is cast, and then permits it to contract, so as to drop out of 65 the flask after the casting is completed, the bar being withdrawn for this purpose. The said bar may be thickened at the back, or formed with a rib, as indicated in Figs. 7 and 5, in order to strengthen it and the shell. At the upper and lower ends the rib is provided with 70 projecting spindles H', to permit the core-barrel to be turned in coating it in the ordinary manner. The core-barrel is perforated, as usual, for the escape of the hot gases, and in order to 75 securely hold the coating compound.

When large castings are to be produced, the shell constituting the core-barrel is provided with internal radial arms, H, two of which are permanently attached to the shell and the other 80 loosely secured thereto, as indicated in Fig. 7 of the drawings, the outer ends of the arms being provided with slots H², through which the bolts P pass, in order that the parts may be 85 properly expanded and contracted.

The section C of the flask is made flaring on the inside, so as to form an enlarged space around the bend at the smaller end of the pipe, and the section d is provided with openings e, which form the gates through which the metal 90 is poured into the mold. At the juncture of the two parts of the flask, on the inside, are formed angular bends g, which are for the purpose of centering the pattern and the pipe when cast within the mold. The flask being 95 empty, is opened and the pipe-pattern inserted. The flask is then closed and the spaces are filled in and rammed with the mixture hereinbefore described. The flask is then opened and the pipe-pattern removed and the mold dried. The 100

bowl-core is then inserted in the recess in the base-plate, and the flask is again closed and latched, and when all is secured the expanding and contracting core-barrel is inserted in the 5 bowl-core, which is tapered to receive it. A grooved ring provided with four openings, to allow the molten iron to enter the mold, is used as a gate. One of the openings serves as a vent. The ring is placed over the core-barrel 10 inside the flask and rests in the mold. The core-barrel properly expanded and coated with the usual material is then placed in the mold, the pattern having been removed. The flask is then closed and locked, when the mold is 15 ready for pouring.

Having thus described my invention, what I claim, and desire to secure by Letters Patent, is—

1. The combination, with the flask con-

structed in two parts hinged together, and provided with locking devices, of the core-barrel 20 having one side divided and grooved at the edges, and the wedge-shaped expanding-bar having spindles at each end, substantially as specified.

2. The core-barrel G, divided longitudinally 25 and having its longitudinal edges provided with V-shaped grooves, in combination with the wedge-shaped expanding-bar G', the edges of which are adapted to fit closely the said V-shaped grooves in the core-barrel, and is thickened or enlarged along its back, as and for the purposes specified.

WILLIAM SMITH.
